MEANS FOR IMPREGNATING

John E. Hoy and Claire S. Harris, Midland,
Mich., assignors to The Dow Chemical Com-
pany, Midland, Mich., a corporation of Michi-
gan

Application April 22, 1937, Serial No. 138,340

6 Claims. (Cl. 91—12.5)

Our invention relates to means for impregnating porous bodies with a fluid substance. It relates more particularly to such impregnation with a substance normally solid but fusible and, more specifically, to the impregnation of porous metal parts, e. g. castings of magnesium base alloys and the like, with a low melting point metal, such as "Wood's metal".

The treatment of non-ferrous alloy castings, specifically magnesium alloy castings, is disclosed in United States Patent No. 2,059,984. The present invention is directed to the provision of means suitable for impregnation purposes and particularly adapted to the process of the above cited patent.

In working the process of the patent, certain problems have arisen calling for solution, among which are the provision of means (1) to evacuate the casting or part to be impregnated, and re-
move gases from the pores thereof, so as to make room for the fluid metal to enter, (2) to apply suitable pressure to force the metal into the pores of the metal part being treated, (3) to fuse and maintain fused the metal employed, (4) to handle parts of various sizes and contours, either singly or in quantity, at one operation.

To the accomplishment of the foregoing and related ends, the invention, then, consists of the means hereinafter fully described and particularly pointed out in the claims, the annexed drawing and the following description setting forth in detail certain means for carrying out the invention, such disclosed means illustrating, however, but one of various ways in which the principle of the invention may be used.

In said annexed drawing:—

The single figure there appearing is a general vertical transverse cross-section of an impregnating apparatus embodying our invention.

In said drawing, 1 is an outer cylindrical shell closed at the bottom by a head 3. An inner shell 2 of cylindrical form is sealed to the lower head 3 and to an annular top head 5. The top head 5 and the outer portion of the bottom head 3 form with the shells 1 and 2 a closed annular compartment 21. The shell 2 with the bottom head 3 and a cover 4 form the inner compartment, or kettle, 22. The head 4 is secured to the top cover 5 by studs and nuts, which may be wing-nuts, as shown at 8. Within the outer compartment 21 is disposed a steam coil 15 having a valved inlet 13 and a valved outlet 14, which inlet and outlet extend through the outer shell 1 and are sealed thereto. A valved nipple 11 is sealed into the shells 1 and 2 to communicate with the kettle 22.

A valved nipple 12 is sealed into the top head 5 to communicate with the compartment 21. A valved draw-off outlet 19 is sealed into the head 3 to communicate with compartment 21. A valved outlet 20 is sealed into the head 3 to communicate with the kettle 22. A capped nipple 10 is sealed into the top head 5 and shell 1 to communicate with the compartment 21 for the purpose of inspection and supply of metal as required. A basket 6, which may be made of perforated plate or of wire cloth, and may be handled in and out of kettle 22 by means of the hooks 7, serves as a container for the castings or other parts to be treated.

The diameters of the shells 1 and 2 are chosen so that the metal-holding capacity of compartment 21 is at least as great, and, preferably, greater, than that of kettle 22. A valve 17 is seated into a valve seat 18 sealed to the inner shell 2, the valve stem continuing out to a hand-wheel 16 operating the valve stem through a stuffing box sealed to the outer shell as shown. This valve permits opening and closing a communication between compartments 21 and 22.

In the operation of the device, the low melting point metal is introduced through 10, the valve 17 being closed. The metal may be added in the molten form and maintained molten by supplying steam to the coil 15. When the desired amount of metal has been introduced into compartment 21, or it has been so filled, the capped nipple 10 is closed. The parts to be treated are put into the basket 6 and with the cover 4 removed the basket with its contents is lowered into the impregnator kettle, after which the cover is applied and bolted down. A vacuum is then applied to the inner compartment by way of valve connection 11 for the purpose of removing occluded or absorbed gases from the parts to be treated. After this has been done the connection 11 may be closed, whereupon the valve 17 is opened, permitting the fluid metal from compartment 21 to enter compartment 22 and rise therein to submerge the parts in the basket 6. When the metal has submerged the parts, the valve 17 may be closed and, if desired, pressure may be applied through the valve connection 11 by introducing compressed air therethrough to further aid in forcing the metal into the parts to be treated. After this has been accomplished, the valve 17 is reopened, whereupon either by the pressure applied through connection 11 or by means of vacuum applied to connection 12 the molten metal is withdrawn from compartment 22 into compartment 21. When this has been ac-

complished, valve 17 is closed, the pressure in the kettle may then be equalized with the room pressure and cover 4 be removed, the basket is lifted out, and the cycle of impregnating operations has 5 been completed. Additional metal may be added as desired through connection 10. In case of intermittent use, the metal in compartment 21 may have been allowed to cool and solidify. It may be remelted by again admitting steam to the coil 10 15, as previously described. We find that steam at 150 lbs. gauge pressure is suitable for use in our apparatus employing a low melting alloy, such as "Wood's metal". The parts to be treated may be preheated, if desired, before introducing them 20 25 into the impregnator. It will be noted that by use of vacuum and/or compressed air the metal may be transferred from compartment 21 to 22 and vice versa. The parts to be subjected to treatment may be put under vacuum to remove 25 30 occluded gases and when submerged in metal may be put under pressure to aid in forcing the metal into them. It will be noted, further, that the apparatus is self-contained and permits maintaining the metal fused at the proper temperature by the choice of proper pressure of saturated steam. It will be noted that by removing the metal from the kettle compartment 22 to the compartment 21 the apparatus is in condition to receive a fresh charge of untreated parts, which 35 40 may then be evacuated, permitting the evacuation and impregnation to be done in one apparatus with but one opening and closing thereof.

Our invention, accordingly, provides a self-contained means for evacuating and impregnating 35 porous bodies with fluid substances, which may be metal, waxes, tars, or other materials, and it is particularly adapted, as described, for the application of the process of the cited patent to the treatment of magnesium base alloy castings.

40 Other modes of applying the principle of our invention may be employed instead of the one explained, change being made as regards the mechanism herein disclosed, provided the means stated by any of the following claims or the equivalent of 45 such stated means be employed.

We therefore particularly point out and distinctly claim as our invention:—

1. In means for impregnating, the combination of a kettle adapted to hold the impregnating agent, a sealable cover therefor, a closed annular compartment about the kettle, a heating element 50 therein, a valved flow connection between the kettle and said compartment and separate flow connections to the annular compartment and the kettle adapted to connect with a source of vacuum or gas pressure.

2. In means for impregnating, the combination of a kettle adapted to hold the impregnating agent, a sealable cover therefor, a closed annular compartment about the kettle, a heating element 55 therein, a valved flow connection between the kettle and said compartment and separate flow connections to the annular compartment and the kettle adapted to connect with a source of 60 vacuum or gas pressure and a removable basket in the kettle adapted to hold an object to be impregnated.

3. In means for impregnating, the combination of a kettle adapted to hold the impregnating agent, a sealable cover therefor, a closed annular compartment about the kettle having a capacity 5 preferably in excess of that of the kettle, a steam heating coil in said compartment, a valved flow connection between the kettle and the compartment so located as to enable transfer of impregnating agent from one to the other, and separate flow connections to the annular compartment and the kettle adapted to connect with a source of vacuum or gas pressure.

4. In means for impregnating non-ferrous metal pieces with a low melting metal, the combination of a vertical cylindrical kettle adapted to hold the fused impregnating metal, a cover therefor sealable to the kettle, a closed annular compartment about and concentric with the kettle wall, a steam heating coil therein, a valved flow connection between kettle and annular compartment 15 adapted to enable transfer of fused metal from one to the other, valved flow connections to the kettle and the annular compartment adapted for connection with a source of vacuum or pressure and a removable basket in the kettle adapted to 20 hold the work to be impregnated.

5. In means for impregnating solid non-ferrous metal pieces such as magnesium base alloy castings with a low melting alloy, the combination of a vertical cylindrical kettle having a removable 30 cover sealable thereto, a closed annular compartment about and concentric with the cylindrical wall of the kettle, which kettle wall is also the inner wall of said compartment, said compartment having a capacity preferably in excess of 35 that of the kettle, a steam heating coil in said compartment, a valved flow connection between the kettle and the compartment so located as to enable transfer of fused alloy from the one to the other, valved flow connections to the kettle 40 and to the compartment, respectively, connectible to a source of vacuum or gas pressure, and a sealable opening to said compartment for introduction of the impregnating agent thereinto.

6. In means for impregnating solid non-ferrous 45 metal pieces such as magnesium base alloy castings with a low melting alloy, the combination of a vertical cylindrical kettle having a removable cover sealable thereto, a closed annular compartment about and concentric with the cylindrical 50 wall of the kettle, which kettle wall is also the inner wall of said compartment, said compartment having a capacity preferably in excess of that of the kettle a steam heating coil in said compartment, a valved flow connection between 55 the kettle and the compartment so located as to enable transfer of fused alloy from the one to the other, valved flow connections to the kettle and to the compartment, respectively, connectible to a source of vacuum or pressure, a removable 60 container in the kettle for the pieces to be treated, and a sealable opening to said compartment for introduction of the impregnating thereinto.
